UNITED STATES PATENT OFFICE.

REME ALBERT BEAUSEJOUR, OF BROOKLYN, NEW YORK, ASSIGNOR TO STANDARD VARNISH WORKS, OF NEW YORK, N. Y., A CORPORATION OF NEW YORK.

LIQUID-COATING MACHINE.

1,204,120.

Specification of Letters Patent.

Patented Nov. 7, 1916.

Application filed July 21, 1909. Serial No. 508,734.

To all whom it may concern:

Be it known that I, REME A. BEAUSEJOUR, a subject of the Crown of Great Britain, and resident of the borough of Brooklyn, in the 5 city and State of New York, have invented a new and useful Improvement in Liquid-Coating Machines, of which the following is a specification.

This invention relates to that type of 10 liquid coating machines in which the articles to be treated to a liquid coating are held in an article holder and raised and lowered by fluid actuated means; and it has particularly to do with the mechanism for 15 raising and lowering the article holder and for steadyng the same in its vertical movement.

One object is to provide fluid actuated 20 means for raising the article holder, which means is adapted to be operated by the gravitational force of liquid flowing from a relatively elevated source, without the necessity of utilizing force pumps.

Another object is to provide new and im- 25 proved mechanisms for rendering the vertical movement of the article holder absolutely even and steady.

With these objects in view, I provide a 30 plurality of cylinders and fluid actuated pistons for raising and lowering the article holder, and I further provide a flexible connection between the pistons for causing them to coöperate in strict uniformity in raising the holder, and a flexible connection between 35 various parts of the lifting bracket, which flexible connection passes over certain fixed supports, as will be hereinafter more fully described.

A practical embodiment of my invention 40 is represented in the accompanying drawings, in which—

Figure 1 represents a view in side elevation, partially in section, of an embodiment 45 of my invention, the bracket and lifting mechanism being shown in their lowered positions in full lines and in their raised positions in dotted lines, and Fig. 2 is a top plan view of the same.

The dipping tank is denoted by 1 and it 50 is provided with a flange 2 for supporting it on the floor or other support 3. The cylinder 4 of a fluid actuated device is located adjacent to the tank 1, and is provided with a collar 5 for supporting it upon the plate 6. 55 The lower end of the cylinder may also rest

upon a support 7. A piston 8 is fitted to reciprocate within the cylinder 4, and its rod 9 extends upwardly through the top of the cylinder.

The fluid inlet pipe is indicated by 10 60 and it has a pressure regulator 11 and a pressure regulator gage 12 therein. This inlet pipe 10 is provided with a branch pipe 13 leading to the upper end of the cylinder 4 and another branch pipe 14 leading to the 65 lower end of said cylinder.

The fluid outlet pipe 15 is connected to the branch pipe 13 through a pipe 16 having a manually operated valve 17 therein. This outlet pipe 15 is also connected to the branch 70 pipe 14 through a pipe 18 having a manually operated valve 19 therein. A manually operated valve 20 is located in the branch inlet pipe 14, and a manually operated valve 21 is located in the inlet pipe 10. 75

The cylinder 22 of a second fluid actuated device is supported by the collar 23 on the plate 6 adjacent to the cylinder 4 of the first-mentioned fluid actuated device. A piston 24 is fitted to reciprocate within the cylinder 22 and its rod 25 extends upwardly through the top of the said cylinder. This cylinder 22 is provided with a fluid inlet pipe 26 having a manually operated valve 27 therein and with a fluid outlet pipe 28 85 having a manually operated valve 29 therein. The fluid inlet pipe 26 of the cylinder 22 is connected to the fluid inlet pipe 14 of the cylinder 4. A bracket is carried by the piston rod 9 above the cylinder 4, which 90 bracket comprises a tubular post 30 surrounding the piston rod 9 and having a horizontal arm 31 projecting from its lower end; and a diagonally arranged supporting strap 32 extending from its upper end to the 95 horizontal arm 31 at a point between the inner and outer ends of the said arm. A vertical post 33 is arranged adjacent to the cylinder 4, which post is of sufficient height to extend above the top of the bracket when 100 the latter is in its raised position. The top of the post is rigidly secured to an upper support 34, and its bottom rests on the plate 6. The upper end of the piston rod 25 is provided with a pulley 35 while a double 105 pulley 36 is mounted in the fixed support 34.

The piston rods 9 and 25 of the fluid actuated devices are interconnected by means of the flexible connection 37, one end of which is attached to a loop 38 at the upper end 110

of the piston rod 9 and the other end of which is attached to the fixed support 39, while the said flexible connection passes over the pulley 36 and under the pulley 35. By 5 reason of the fact that the pulley 35, mounted on the upper end of the piston rod 25, is supported in a bight of the flexible connection 37, while the piston rod 9 is attached to one end of the said flexible connection, 10 the piston 24 will be free to travel only one-half the distance that is traveled by the piston 8 in raising the article supporting bracket to any predetermined extent.

To insure an even vertical movement of 15 the bracket, I provide upper and lower guide pieces 40, 41, mounted on a tubular post 30, and each carrying a pair of rollers 42 which engage the post 33 on opposite sides thereof, thus causing the tubular post 20 30 to remain exactly parallel with the post 33 during the vertical movement of the bracket. In further carrying out this same purpose, and to prevent any wobbling or vibration of the bracket as it is raised or 25 lowered, I provide a support for the outer end of the horizontal arm 31 which is arranged in the following manner:—A flexible connection 43 is attached to the outer end of the horizontal arm 31. It then passes over 30 the pulley 44 conveniently mounted in a suitable upper support 45 directly over the end of the arm 31; thence over the double pulley 36; thence around the pulley 46, mounted in the horizontal lug 47 near the 35 lower end of the post 33; and is then attached to the lower guide piece 41. This flexible connection 43 is drawn taut with the arm 31 exactly at right angles to the tubular post 30, and serves admirably as a 40 support for the arm 31 to prevent any trembling thereof in its vertical movements, which tremors might be imparted to the article supported from said bracket during the dipping operation and thus mar the 45 coating received by the article. The article holder 48 is removably secured to the arm 31 by the catch 49, and steadied in this position by the props 50.

In operation, presupposing the bracket to 50 be in its lowered position indicated in full lines in Fig. 1, fluid is admitted through the inlet pipe 10 and thence through the branch inlet pipes 14 and 26 to the cylinders 4 and 22 respectively; and, at the same time, 55 motive fluid is allowed to escape from the cylinder 4 through the pipes 16, and 15, but the outlet pipe 28 from the cylinder 22 is kept closed. The fluid entering the cylinder 4 will raise the piston 8 therein and the article supporting bracket will be raised along with it. The motive fluid entering the cylinder 22 will depress the piston 24 and thus assist in raising the article supporting bracket by reason of the fact that the pistons 24 and 8 are interconnected by the

flexible connection 37 which passes over the fixed pulley 36 at a point between its points of engagement with the pistons 9 and 24. When it is desired to lower the article bracket, the motive fluid is allowed to escape from the cylinder 4 through the pipes 18 and 15 and from the cylinder 22 through the pipe 28, while motive fluid is allowed to enter the cylinder 4 through the pipes 10 and 13. It will thus be seen that the fluid 75 actuated device, comprising, in general, the cylinder 22 and piston 24, operates actively only in raising the bracket, while the other fluid actuated device operates actively both in raising and lowering the bracket. 80

By utilizing a plurality of fluid actuated devices, I am enabled to raise the bracket and articles of considerable weight secured thereto, by means of the mere gravitational force of liquid flowing from a relatively elevated source, without the aid of force pumps. Moreover, the novel manner in which the fluid actuated devices are interconnected insures an absolutely even speed of movement of the bracket as it is raised and lowered, 85 and further assists the steadyng devices, heretofore described, in preventing any wobbling or trembling of the bracket, as it is raised or lowered. The fact that the fluid inlet pipes 26 and 14 are in communication 90 with each other insures an even pressure in both cylinders as the article holding bracket is being raised.

It is obvious that various changes may be resorted to in the form, construction and arrangement of the different parts of this machine without departing from the spirit and scope of my invention; hence I do not wish to limit myself strictly to the construction herein shown and described, but 100

What I claim is:

1. In a machine of the character described, a tank, an article supporting bracket, a steadyng device engaging both ends of the bracket, and a plurality of raising and lowering devices for said bracket. 110
2. In a machine of the character described, a tank, an article supporting bracket, a flexible steadyng device engaging both ends of the bracket, and a plurality of raising and lowering devices for said bracket. 115
3. In a machine of the character described, a tank, an article supporting bracket, a flexible steadyng device engaging both ends of the bracket, and a plurality of fluid operated raising and lowering devices for said bracket. 120
4. In a machine of the character described, a tank, an article supporting bracket, a plurality of interconnected devices for raising and lowering the bracket, and flexible means connected to one of said devices for steadyng the bracket in its vertical movement. 125
5. In a machine of the character described, 130

a tank, an article supporting bracket, a plurality of fluid operated interconnected devices for raising and lowering the bracket, and flexible means connected to one of said devices for steadyng the bracket in its vertical movement.

6. In a machine of the character described, a tank, an article supporting bracket, a plurality of oppositely acting interconnected devices for raising and lowering the bracket, and flexible means connected to one of said devices for steadyng the bracket in its vertical movement.

7. In a machine of the character described, a tank, an article supporting bracket, a plurality of fluid operated oppositely acting interconnected devices for raising and lowering the bracket, and flexible means connected to one of said devices for steadyng the bracket in its vertical movement.

8. In a machine of the character described, a tank, an article supporting bracket, a plurality of devices for raising and lowering the bracket, a fixed pulley, a pulley carried by one of the devices, a fixed support, and a flexible connection secured to the other raising and lowering device and to the fixed support and engaging the said pulleys.

9. In a machine of the character described, a tank, an article supporting bracket, a plurality of devices for raising and lowering the bracket, a fixed pulley, a flexible connection engaging each of said devices and

passing over the said pulley, and means for steadyng the bracket in its vertical movement.

10. In a machine of the character described, a tank, an article supporting bracket, a plurality of devices for raising and lowering the bracket, a fixed pulley, a pulley carried by one of the devices, a fixed support, a flexible connection secured to the other raising and lowering device and to the fixed support and engaging the said pulleys, and means for steadyng the bracket in its vertical movement.

11. In a machine of the character described, a tank, an article supporting bracket, and a plurality of raising and lowering devices of different capacity for raising and lowering the bracket.

12. In a machine of the character described, a tank, an article supporting bracket, and a plurality of fluid operated raising and lowering devices of different capacity for raising and lowering the bracket.

In testimony, that I claim the foregoing as my invention, I have signed my name in presence of two witnesses, this nineteenth day of July 1909.

REME ALBERT BEAUSEJOUR.
